UNITED STATES PATENT OFFICE.

ERICH SCHIETZEL, OF WILKES-BARRE, PENNSYLVANIA.

SPARKER DEVICE.

No. 905,935.

Specification of Letters Patent.

Patented Dec. 8, 1908.

Application filed January 8, 1908. Serial No. 409,874.

To all whom it may concern:

Be it known that I, ERICH SCHIETZEL, a subject of the Emperor of Germany, residing at Wilkes-Barre, in the county of Luzerne and State of Pennsylvania, have invented certain new and useful Improvements in Sparker Devices; and I do hereby declare the following to be a full, clear, and exact description of the invention, such as will enable others skilled in the art to which it appertains to make and use the same.

This invention relates to improvements in means for exploding blasting charges in mines, and particularly to means that may be operated upon the surface of the ground to explode one or more blasting charges within the mine.

The invention comprises the provision of a switch designed to be manually operated, for connecting a blasting charge across the line of a pair of line wires, and means for throwing current on the said line wires for discharging said blasting charge and for at the same time energizing means for throwing said switch.

The invention further comprises means that may be arranged in various parts of the mine for connecting blasting charges to wires adapted to carry electrical current, and means positioned on the surface of the earth for supplying current to said line wires and said blasting charges, whenever desired.

The object in view is the provision of a switching device arranged to be placed in each chamber of a mine; and to be connected to the line wires extending to the surface of the earth, and to also be connected to the fuse of a blasting charge so that when the current is turned on said line wires extending to the surface of the earth, said fuse will be ignited.

Another object in view is the provision of a switching device connected to a fuse and connected to line wires extending to the surface of the earth so that when the line wires are charged with current, the fuse will be ignited, and the switch actuated for automatically igniting a second fuse of a series after the first fuse is ignited.

With these and further objects in view, the invention comprises certain novel constructions, combinations and arrangements of parts as will hereinafter be more fully described and claimed.

In the accompanying drawing, the figure

represents a view partially in section, showing a switch and operated mechanism therefor, in connection with wiring of a mine.

In mining, after an explosive charge has been placed in position, the same must be exploded by some means, as for instance, by fuse or electrical spark, and during the explosion, the miners must take a position considerably distant from the explosion so as to not be affected thereby, and so as to not be in a position where any caving-in of the mine will be likely. In order to provide a device in which the miner may set his explosive charge and fuse, and then leave the vicinity of the charge or leave the mine if desired, I have provided a switch 1 inclosed in a suitable housing, and a plurality of wirings connected thereto and to a fuse and also to a source of current. In applying the present invention, the same may be applied to one of the line wires 2 of the mine, or may be provided with a complete metallic circuit of its own as may seem most desirable. The switch 1 is provided with suitable framework or housing that has an electro-magnet 3 secured thereto. The electro-magnet 3 is provided with an armature 4 that extends into the magnet 3 any desirable distance and engages a spring 5 that normally tends to force outward armature 4. Formed on armature 4 is an extension 6, arranged to engage a catch 7 either at notch 8 or notch 9. The catch 7 is provided with a stop 10, against which the extension 6 rests when the catch 7 is in its outer position. Stop 10 also is designed to be engaged by spring 11 that encircles one end of catch 7.

A stop 12 is also provided, through which catch 7 is designed to reciprocate and to act as a stop or shoulder for one end of spring 11, so that spring 11 may at all times exert a tendency upon catch 7 to force the same in an outer position, as shown in full lines in the drawing. Rigidly secured to one end of catch 7 are a plurality of contact members 13, 14 and 15. These contact members are insulated from each other at 33 and 34, and also from catch 7 at 35, by any desired kind of insulation, so as to prevent any sparking or short circuiting of the current.

One of the line wires 2 is connected to a binding post 16, which in turn is connected to the winding of magnet 3. Connected to the opposite end of the winding, is a wire 17, which in turn is connected to contact 13. Wire 17 also has a branch 18 that is attached

to binding post 19, which in turn is connected with a fuse 20, used in discharging a blasting charge of any desired kind. The fuse 20 is also connected to one of the wires 2, so that when current passes from line wire 2 to the magnet 3 through binding post 16, current will also pass through fuse 20, binding post 19, wire 18, wire 17 and on to flexible contact 13.

10 In operation, the fuse 20 is placed in position in an explosive charge of any desired kind, at any desired place in the mine, and then the fuse 20 is connected to one of the wires 2 and to binding post 19. After this 15 has been done, catch 7 is forced inward against action of spring 11, until extension 6 is in engagement with the notch 9. When catch 7 is moved to this position, the flexible or spring contacts 13, 14 and 15 are moved 20 to the dotted position, and the central contact 14 is permitted to spring or move over against contact 13, as clearly shown in dotted line. A suitable contact member 21 is provided for bridging the space between 25 members 13 and 14 when member 14 is permitted to take its normal position, shown in dotted lines in the drawing. When catch 7 is forced to the rear, member 14 will also be forced to the rear, and move from beneath armature 4, which normally holds the 30 same in the position shown in full lines with the bridging member 21 in contact with contact member 15. After the contact members 13, 14 and 15 have been moved to the 35 dotted position, the device is set ready to be exploded when switch 22 is closed. When a miner, in any of the chambers or parts of the mine, has set the switch by properly connecting fuse 20 to the line 2 and to the 40 binding post 19, and then pushed catch 7 to the dotted position shown in the drawing, he leaves his place and goes to some place of safety, as for instance, the surface of the ground. The various other miners also set 45 their fuses and force their various catches 7 inward, as may be desired, and then also go to the surface of the ground preparatory to exploding the various charges placed in position by them. After the miners have all 50 reached the ground, switch 22 is closed. The current passing from battery 23 will flow through wire 24 to wire 2 and thence to fuse 20, through fuse 20 to binding post 19, wire 18, wire 17 and contact 13, contact 14, wire 25, binding post 26, wire 27, wire 28, back to the source of current 23, through switch 22. When the current flows in this circuit, it will form a spark in fuse 20 and ignite the same so as to explode the explosive charge to which the fuse is secured. At the same instant that the current flows through fuse 20, it also branches off and flows through binding post 16, windings of magnet 3, wire 17, contact 65 13, contact 14, wire 25, binding post 26, wire

27, wire 28, and from thence to the source of current 23 through switch 22. As the current flows through the windings of magnet 3, armature 4 will be moved upward, and extension 6 will be moved out of notch 70 9 into which the same drops when catch 7 was forced to the above position in the drawing. As soon as armature 4 and extension 6 are raised, catch 7 will be immediately moved by spring 11 to the position shown in 75 the full lines on the drawing.

The fuse 20 is ignited practically at the same time the magnet 3 is energized, the ignition of the fuse serving to break the circuit in which it was interposed prior to the 80 explosion, and as soon as the explosion takes place, the switch 22 is momentarily opened thereby deenergizing the magnet 3 permitting its armature or core 4 to drop to full line position in the drawings. This movement of the core of the magnet will bring the contact point of the contact 14 into engagement with the contact 15 and the circuit will be closed, except for the switch 22, through the system of wiring in which the 85 second fuse and circuit closing device is interposed, closing of the switch 22 serving to complete the said circuit and actuate the 90 second circuit closing device just mentioned, exploding the second fuse. 95

In mines, line wires as 2 are provided for supplying lamps 29 with current for lighting the mine in any desired way. To one of these line wires is secured any desired number of switches as 1, which use as a return, wire 28, binding post 26, wire 25, contact 14, contact 15, wire 30, and wire 31. Wire 31 is connected to binding post 32 in the first switch as 1, and to the binding post as 26 in the second switch as 1. The binding post 32 of the second switch is connected by wire 31 to the binding post as 26 of the third switch as 1, and so on until the mine is completely wired. If the fuse 20 is not provided or set in the first switch as 1, current will pass over wire 2 to the second switch as 1, and after doing its work there, 100 will return over 31, wire 30, contact 15, contact 14, wire 25, binding post 26, wire 27, wire 28, and back to the source of current 105 23 through switch 22. 110

In tracing the circuit it will be observed that there is a principal circuit and a plurality of auxiliary circuits. When switch 22 is closed current passes through first the 115 principal circuit and one of the auxiliary circuits, and then the other auxiliary circuits as the various switches are operated. Immediately upon the closing of the principal circuit the electromagnet is energized, 120 whereby the core 4 moves and permits the current to be switched to a second auxiliary circuit. By thus constructing a principal circuit and a plurality of auxiliary circuits 125 when the principal circuit is closed current 130

is left to pass through the same and one of the auxiliary circuits after which that particular auxiliary circuit is cut out and a second auxiliary circuit is switched in with the principal circuit whereby the various fuses receive a spark.

What I claim is:—

1. In a circuit closing system of the class described, a principal circuit, a plurality of auxiliary circuits, a plurality of contacts in the principal circuit and in each of the auxiliary circuits, two of the contacts being normally in engagement, an electro-magnet in the principal circuit, a core for the magnet, the said core being arranged to engage with one of the said contacts upon deenergization of the magnet to move the said contact into engagement with the remaining one of the plurality of contacts and thereby close the circuit through the next succeeding auxiliary circuit, and a switch interposed in the principal circuit and common to all of the circuits.
2. In a circuit closing device of the class described a principal circuit, an auxiliary circuit, normally engaging contacts in the principal circuit, a third contact in the auxiliary circuit, an electro-magnet, a core for the magnet, the said core being arranged to engage with one of the first mentioned contacts upon deenergization of the magnet to bring the said contact into engagement with the contact in the auxiliary circuit to connect the said circuit with the principal circuit, and a switch in the principal circuit common to both circuits.
3. In a circuit closing device of the class described, an electro-magnet, a set of three contacts, a plunger carrying said contacts,

two of the contacts being normally in engagement, a core for the electro-magnet engaged normally with the plunger to hold the same with the contacts out of position for engagement by the core of said magnet, the said plunger being arranged to be released upon energization of the said magnet, a spring acting to shift the plunger when so released to bring the contacts into operative position with respect to the core of the magnet, deenergization of the magnet acting to release said core whereby said core moves one of said two first mentioned contacts into engagement with the third contact, and a switch interposed in the circuit for the said magnet.

4. In a circuit closing system of the class described, a principal circuit, a plurality of auxiliary circuits, a plurality of contacts in the principal circuit and in each of the auxiliary circuits, two of said contacts being in engagement at a time, an electro magnet in the principal circuit, a reciprocating armature therefor, a projection secured to said armature, a reciprocating catch carrying said contacts, said armature being adapted to engage one of said contacts upon the deenergization of the magnet for moving said contacts, and said projection on said armature being adapted to engage said catch, and a switch interposed in the principal circuit and common to all of said circuits.

In testimony whereof I affix my signature in presence of two witnesses.

ERICH SCHIETZEL.
